INVENTORS.

UNITED STATES PATENT OFFICE.

ELMER E. HERSH, BENJAMIN F. WOODWARD, AND JOHN W. PETTEE, OF DENVER, COLORADO.

CIRCUIT-SWITCH.

SPECIFICATION forming part of Letters Patent No. 518,188, dated April 10, 1894.

Application filed October 25, 1893. Serial No. 489,144. (No model.)

To all whom it may concern:

Be it known that we, ELMER E. HERSH, BENJAMIN F. WOODWARD, and JOHN W. PETTEE, citizens of the United States of America, 5 residing at Denver, in the county of Arapahoe and State of Colorado, have invented certain new and useful Improvements in Circuit-Switches; and we do declare the following to be a full, clear, and exact description of the 10 invention, such as will enable others skilled in the art to which it appertains to make and use the same, reference being had to the accompanying drawings, and to the letters and figures of reference marked thereon, which form a 15 part of this specification.

Our invention relates to improvements in circuit switches, and though especially designed for use in electric light circuits, we do not limit ourselves to this use since we are 20 aware that it may be advantageously employed in many other relations.

Our object in bringing forth this invention is to provide a device of the class stated which shall be simple in construction, economical in 25 cost, reliable, durable and efficient in use; and to these ends the invention consists of the features hereinafter described and claimed, all of which will be fully understood by reference to the accompanying drawings in which 30 is illustrated an embodiment thereof.

In the drawings, Figure 1 is a front end view of the device with the face plate removed. Fig. 2 is a similar view with the actuating leaf-spring removed. Fig. 3 is a 35 rear view with the face plate in position. Fig. 4 is a section taken on the line $x-x$, Fig. 3. Fig. 5 is a section taken on the line $y-y$, Fig. 3. Fig. 6 is a perspective view of a rotatable switch-block, whereby the current is 40 alternately made and broken. Fig. 7 is a perspective view of a leaf-spring forming the actuating dog for the switch-block shown in Fig. 6. Fig. 8 is a diagrammatic view illustrating the duplex circuit, whereby the lamp 45 or series of lamps, is controlled from two separate points. Fig. 9 is a fragmentary view showing a modified form of construction. Fig. 10 is a perspective view of a single pole T-switch block.

50 Similar reference characters indicating corresponding parts or elements of the mechan-

ism in the several views, let the numeral 5 designate a cylindrical casing composed of some suitable insulating material, as glass or porcelain. This casing is provided with an 55 exteriorly projecting circumferential rim 5^a and a central, apertured partition 5^b. The rim of the casing is provided with two notches or recesses 5^c preferably located diametrically opposite each other, and adapted to receive the angular locking lugs 6^a of the face plate 6. After the lugs have entered the recesses of the rim, the face plate is locked to the casing by a partial revolution, whereby the interior projections of the lugs are made 65 to pass under the rim. The face plate is centrally depressed as shown at 6^b, and apertured to receive the push-button 7 whose outer extremity is normally flush, or in the same plane with, the body of the plate. 70

Located in the aperture formed in the partition 5^b of the casing, is the double T-shaped integral switch-block composed of the head 8, the oppositely disposed stems 8^a and 8^b, and the pivots 8^c formed upon the respective 75 stems. This switch-block is composed of some suitable material, as metal forming a good conductor of the electric current. The pivots of the switch-block are located in recesses 5^d formed in the central partition of the casing, and are held in place by the double contact brush 9 secured to one surface of the partition by a pair of binding screws 10. The arms 9^a of this double brush are alternately in engagement with the stems 8^a and 8^b of the 80 switch-block, whereby the latter is held securely in place and prevented from slipping out or moving in the recesses which its parts engage. To the opposite face of the partition 5^b are attached two separate contact brushes 12 and 12^a also secured by binding screws 10, and alternately in engagement with the stems of the T-shaped switch-block as the latter is rotated. The binding screws all project from the rear side of the partition and are made 90 fast by screws 13 on the opposite side. The contact brushes must all be composed of some material forming a good electrical conductor, preferably copper. 95

Attached to the same surface of the partition as the double brush, but external thereto, is a spring for actuating the T-shaped switch- 100

block. The base of this spring is composed of the two outer arms 14 which engage the respective arms of the double brush 9, and the central arm 14^a which is in continuous engagement with the head of the T-shaped switch-block. These arms of the spring are formed by cutting two slits in its base, the object being to allow the different parts to yield independently of each other during the rotation or movement of the switch-block. The upper portion 14^c of the spring terminates in a hook-shaped projection 14^d and is sufficiently separated from the base to permit the movement necessary for actuating the switch-block. The projection 14^d of the spring is normally located in close proximity to the head of the switch-block, which is provided with shallow recesses 8^e for the reception of said projection as the same is pressed to actuating engagement with the switch-block. The part 14^c of the spring is apertured to receive a projection 7^a of the push-button 7 which is provided with a shoulder 7^c, normally, or when at its outward limit of movement, engaging the inner surface of the depressed portion 6^c of the face plate. The relation between the rotatable switch-block, the spring and the push-button must be such that the switch-block is given a quarter rotation every time the button is pressed.

From the construction shown and heretofore described, it will be observed that the double brush 9 is always in contact with the rotatable switch-block, while the brushes 12 and 12^a are alternately in contact therewith as the switch-block is rotated. In the drawings, four binding posts are illustrated, two being connected with the double brush 9. All of these posts would never, however, be used, except in the double pole form of the switch. In all other cases, one of the posts connected with the double brush may be dispensed with, while if it is desired to control the lamp, or lamps, from but a single point, only one of the brushes 12 or 12^a is needed, since the circuit is alternately made and broken by the use of the double brush and either of the single brushes. When it is desired to control the lights from two points, employing the single pole system, a switch having both single brushes and the double brush, is employed at each point. In this case, however, only one binding post in connection with the double brush is needed, since but one wire leads to said brush of each switch.

We have thought it necessary, only to illustrate the circuit in which the lamp is controlled from two points, and this is shown in Fig. 8. Referring now to this figure, let A and B designate the two switches, 15 the lamp, 16 and 17 the wires of the main circuit, 18 the wire leading from the main circuit to the double brush of the switch A, 19 the wire leading from the main circuit to the lamp, 20 the wire leading from the lamp to the double brush of the switch B, and 21 and 22 the wires

connecting the single brushes of the respective switches. Assuming now that the T-shaped switch-blocks are in the position shown in this figure, the current may be said to pass from wire 17 to wire 17 via the following route, the elements being named in order: wire 19, lamp 15, wire 20, brush 9, the T-shaped switch-block and brush 12 of switch B, wire 22 to brush 12 of switch A, and the T-shaped switch-block and brush 9 of same switch, and thence via wire 18 to main wire 17, the circuit being closed and the lamp lighted. Now, if by pressing the push-button of either switch A or B, the T-shaped switch-block of the corresponding switch is given a quarter rotation, the circuit will be broken and the lamp extinguished. Again, if the T-shaped switch-blocks of both switches A and B are given a quarter rotation from the position shown in Fig. 8, the circuit will again be closed and the current may be said to pass from wire 16, via wire 19, lamp 15, wire 20, brush 9, the T-shaped switch-block and brush 9 of switch A, and thence via wire 18 to the main wire 17. The central or depressed portion of the face plate is formed separate from the body of the plate as illustrated in Fig. 9, in which the central depressed portion is designated 6^c.

Having thus described our invention, what we claim is—

1. The combination of the casing provided with the apertured partition, a T-shaped rotatable switch block pivoted in said partition, two contact brushes attached to opposite surfaces of the partition and adapted to engage the block, an apertured face plate, and a single push button for actuating the switch block, substantially as described.

2. In a circuit switch, the combination with a suitable casing, of a double T-shaped rotatable switch-block, and two contact brushes, one double and the other single, engaging the opposite stems of the switch-block, and suitable means for actuating the switch-block, substantially as described.

3. In a circuit switch, the combination with the rotatable switch-block, the two contact brushes, one double and the other single, the single push-button and the intermediate spring for actuating the switch-block, the arrangement of the parts being such that one of the brushes is always in contact with the switch-block, while the other is alternately in contact therewith as the latter is rotated, substantially as described.

4. In a circuit switch, the combination with the casing of the rotatable double T-shaped switch-block, the double contact brush, the two single brushes, the single push-button and the intermediate spring, the arrangement being such that the double brush is always in contact with the switch-block, and the two single brushes alternately in contact therewith as the switch-block is rotated, substantially as described.

5. In a circuit switch, the combination of

the casing having a notched rim at one extremity, and a central apertured partition, the operative parts of the switch mechanism being attached to said partition, and the face plate provided with lugs adapted to engage the rim of the casing, and apertured to receive the actuating push-button, substantially as described.

6. In a circuit switch, the combination with the casing and apertured face plate, of the double T-shaped rotatable switch-block, the contact brushes engaging the stems of the switch-block, the leaf spring normally located in close proximity to the switch-block, and the single push-button engaging the spring, substantially as described.

7. In a circuit switch, the combination of the casing having the notched rim at one extremity, the central, apertured partition, a T-shaped rotatable switch block pivoted in said partition, two contact brushes attached

to the opposite surfaces of the partition and adapted to engage the block, an apertured face plate provided with lugs adapted to engage the rim of the casing, and a single push button for actuating the switch block, substantially as described.

8. In a circuit switch, the combination of the cylindrical casing having the apertured face plate, and the centrally apertured partition, a T-shaped rotatable switch block pivoted in the partition, a single push button, an intermediate spring, and suitable contact brushes, substantially as described.

In testimony whereof we affix our signatures in the presence of two witnesses.

ELMER E. HERSH.
